(57) **CLAIM**

The ornamental design for a shoe, as shown and described.

DESCRIPTION

FIG. 1 is a bottom perspective view of a shoe taken from a first side of the shoe showing my design;

FIG. 2 is a bottom perspective view thereof taken from a second side of the shoe;

FIG. 3 is a bottom view thereof;

FIG. 4 is a bottom perspective view thereof taken from the front of the shoe; and,

FIG. 5 is a bottom perspective view thereof taken from the rear of the shoe.

The even-length broken lines are directed to environment, represent unclaimed subject matter, and form no part of the claim.

1 Claim, 5 Drawing SheetsFIG. 3

FIG. 4

FIG. 5
